UNITED STATES PATENT OFFICE.

MARSHALL O. ROBERTS, OF WASHINGTON, DISTRICT OF COLUMBIA.

DESIGN FOR A SCARF.

SPECIFICATION forming part of Design No. 22,495, dated June 6, 1893.

Application filed April 27, 1893. Serial No. 472,132. Term of patent 7 years.

To all whom it may concern:

Be it known that I, MARSHALL O. ROBERTS, a citizen of the United States, residing at Washington, in the District of Columbia, have 5 invented and produced a new and original Design for Scarfs; and I do declare the following to be a full, clear, and exact description of the same, reference being had to the accompanying drawing, forming a part thereof.

10 My invention has reference to scarfs of the character known in the art as "ready made" scarfs, and has for its object to produce a scarf of a new and original design, which shall be neat and attractive, and unique in its appearance.

15 My invention consists in a scarf having the "knot" portion thereof shaped to the form of a shield, and having its ends shaped to conform to the lower portion of a shield; and 20 consists also in the representation of a flag on the said knot portion.

In the accompanying drawing which forms 25 a part this specification I have shown in elevation a scarf illustrating my design, and in which the reference letter *a* denotes the knot portion, *b b*, the ends of the scarf, *c*, the band,

and *d* a representation of a flag on the knot portion. The knot portion *a* is shield-shape in its general contour, and the band *c* is connected to the same at opposite sides and at 30 the top thereof. The ends *b b* of the scarf extend from the lower end of the knot portion downward, and terminate in contours conforming to the lower portion of a shield. On the knot portion is the representation *d* 35 of a miniature flag and staff which is arranged lengthwise of the knot.

The design as a whole is unique in its general contour, and may be made very attractive in appearance.

40 What I claim is—

The design for a scarf herein shown and described, the same comprising the shield-shaped knot portion, the representation of a flag thereon, and the shield-shaped ends, as 45 set forth.

In testimony whereof I affix my signature in presence of two witnesses.

MARSHALL O. ROBERTS.
